(57) CLAIM

I claim the ornamental design for footwear, as shown and described.

DESCRIPTION

FIG. 1 is a perspective view of footwear, showing my new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The small dashed lines on the footwear upper represent claimed stitching. The larger dashed lines on the laces and outsole are included for illustrating environmental structure and form no part of the claimed design.
